United States Patent Office.

JOHN K. WRIGHT, OF PHILADELPHIA, PENNSYLVANIA.

Letters Patent No. 91,191, dated June 8, 1869.

IMPROVEMENT IN PRINTING-PRESSES.

The Schedule referred to in these Letters Patent and making part of the same.

To all whom it may concern:

Be it known that I, JOHN K. WRIGHT, of Philadelphia, Pennsylvania, have invented a new and useful Printing-Press; and I do hereby declare that the following is a full and exact description of the construction and operation of the same, reference being had to the annexed drawings, forming part hereof, and to the several letters marked thereon, in which drawings—

Figure 1 is a perspective view of the press, one side of the frame being removed, or only outlined in red ink.

Figure 2 is an elevation of the off side of the frame.

Figure 3 is a perspective view of the printing-cylinders and inking-rollers broken off, showing the sockets, enclosed bearings, and attached springs, relating to these rollers, and also the cams, which act on said rollers to press them way from the printing-cylinders at proper times, as hereinafter described.

Figure 4 is a perspective view of a single printing-cylinder, showing the removable sliding surface plate, which holds the form of types, also the longitudinal grooves in which the tongues on said plate slide.

My invention relates chiefly to presses which print both sides of a sheet at one operation.

In the drawings—

a represents the frame, which may be of cast-iron, braced together with cross-rods.

b, *c*, and *d*, are the type-cylinders, on the shaft of each of which, outside of the frame, there is a cog-wheel, *e*, fig. 1; these several wheels gearing into each other, as shown.

f and *g* are drums or pulleys, around which the endless flexible or jointed frisket *h* passes.

The journal-boxes *i*, of these drums *f* and *g*, are adjusted toward or from each other, so as to tighten or slacken the frisket *h* by means of the screws *j*.

k and *l* are endless belts, of steel or leather, or any suitable material, also passing around the pulleys *f* and *g*, these belts being attached to the frisket *h* by the metallic cross-pieces *m* of the frisket extended, or in any other desired manner.

Each cross-piece *m* is provided with projecting sharp points, *n*, which pierce and hold the paper in place on the frisket as it (the paper) is drawn from the paper-roller *o*, between the printing-cylinders, to the place of discharge.

On the roller *o* there is wound a strip of blank paper, of any desired length, to be printed upon.

p, *q*, *r*, *s*, *t*, *u* are rollers, around which pass the belts *v*, which are in close contact with the roll of paper on roller *o*, the journals of which turn in open sockets, as at *w*.

The roller *u* carries the cog-wheel *x*, fig. 2, which gears into the cog-wheel *y*.

The journals of roller *t* have bearings in two arms, *z*, which are attached to the frame *a* of the machine

by bolts or pivots, as shown, allowing said roller *t* to be turned up out of the way, when it is desired to remove or introduce the paper-roller *o*.

The location of roller *t* is such as to increase the friction or driving-power of the belts *v* on the roll of paper, by causing said belts to embrace a large part of the circumference of the roll of paper, thus causing the paper on the paper-roller to unwind correctly.

The roller *r* takes up any slack of the belts *v*, caused by the gradual decrease in the size of the roll of paper as it is unwound.

The journals of said roller *r* have bearings in slots in the frame of the machine, one of which slots, partially covered by the removable guard *a'*, is shown in fig. 2.

b' are springs, secured in place in the bearings of roller *r* by guards *a'*.

These springs allow the roller *r* to adjust itself freely to the variation in the tension of the belts *v*, such variations being caused, as before mentioned, by the decrease in the size of the roll of paper.

The printing-cylinders *b*, *c*, *d* are similar in all respects, the circumference or surface around each cylinder corresponding with the width of the frisket, being half "form" and half "blanket;" the form on cylinder *b* being arranged thereon, so that when the cylinders are in motion, said form comes opposite to the blanket on cylinder *c*, and the form on cylinder *c* comes opposite to the blanket on cylinder *b*.

The form on cylinder *d* is arranged so that when the cylinders are in motion, said last-mentioned form comes opposite to the blanket on cylinder *c*, and the form on cylinder *c* comes opposite to the blanket on cylinder *d*, thus producing four impressions by one revolution of the printing-cylinders.

c', *d'*, *e'*, *f'*, *g'*, *h'*, *i'*, *j'*, fig. 3, are inking-rollers, of which rollers *e'*, *f'* and rollers *g'*, *h'* are on opposite sides of the middle printing-cylinder *c*.

The journals of said inking-rollers revolve in slotted sockets *k'*, each of which encloses a movable journal-bearing, *m'*, and a spring, *n'*, the springs and bearings being connected.

The sockets *k'* are slotted, as shown.

Cams *o'* are secured, one to each end of the printing-cylinders *b*, *c*, *d*, said cams being arranged as shown.

By the action of said cams *o'*, the inking-rollers are forced away from the printing-cylinders, so as not to be in contact with the blanket-portion thereof, and by the action of said springs *n'*, the inking-rollers are forced toward the printing-cylinders at the proper time to come in contact with the type-portion or "form" thereof.

The discharging-apparatus consists of a drum or cylinder, *p'*, which constitutes the base to which other parts are attached.

This cylinder *p'* rotates on its axis *q'*, which has bearings in the frame *a* of the machine, and carries

on one end the cog-wheel x' , which gears into the cog-wheel y , which gears into the cog-wheel t' , which gears into the cog-wheel u' , as shown in fig. 2.

The circumference or girth of cylinder p' is divided into any number of equal-sized sections, each of which corresponds in length, measuring around the cylinder, with one of the sections or subdivisions of any of the printing-cylinders.

v' are flat springs, fastened at one end to the cylinder p' , and provided with cross-bars w' at their other or free ends.

The cross-bars w' extend beyond the length of the cylinder p' , the ends of said bars sliding upon the inner sides or edges of two curved tracks or cams x' .

These bars w' also carry each a serrated knife, y' , said knives being secured to said bars.

z' is a narrow plate extending longitudinally across the cylinder p' , in close proximity to the sharp points s' , and operating as an auxiliary fly at the same time that it relieves the paper from the sharp points.

Plate z' is attached to two arms, which work through spiral springs a' in recesses b' in the cylinder p' , said arms being provided with projecting pins c' , which, in the revolution of cylinder p' , come in contact with two stationary cams d' , fastened to the opposite sides of frame a of the machine.

e' is a device, operating as a following-fly, composed of flat springs or fly-rods f' , connected by a cross-piece, g' , the ends of which extend far enough beyond cylinder p' to enable them to run on guide-tracks or cams h' , said flat springs f' being attached, at one end, to the cylinder p' , at the same points where the springs v' are attached. Said following-fly e' having more elasticity than the fly which carries the knife y' , follows the cut-off sheet directly down to the receptacle or pile of printed sheets below, and then instantly springs up, remains in contact with cross-bar w' , and is carried away by the motion of cylinder p' .

s' are projecting sharp points, which pierce the paper, and thus hold it on the cylinder p' .

Each section of cylinder p' is provided with projecting sharp points, a fly, an auxiliary fly, and a following-fly, similar to those described.

f^2 and g^2 are rollers revolving in contact with cylinder p' .

h^2 is a serrated circular knife on the roller g^2 , the serrations of said knife running in a groove formed in the circumference of the cylinder p' . This knife is caused to revolve by proper mechanism more rapidly than the cylinder p' , for the purpose of slitting the sheet when desired.

i^2 , fig. 1, is a trough, or receptacle for steam or water. It is perforated at the bottom, to allow sufficient water or steam to escape on to the endless belts v , or blanket, which partially embrace the paper on the paper-roller, to dampen said belts, or blanket, which, in turn, dampen the blank paper as it is unrolled.

The frame a , on one side or the other of the press, or on both sides, if desired, is cut away, forming an aperture, as at k^2 , fig. 2; opposite the middle printing-cylinder c , to facilitate the placing of the type upon the last-named cylinder, the cog-wheel u' , or wheels u and e , being temporarily removed for the purpose.

m^2 , fig. 4, is a metallic plate, which is bent so as to be in conformity with the curve of the printing-cylinder to which it is applied.

Its edges are turned over slightly, so as to form tongues, which slide in two similar grooves n^2 , while they at the same time hold the plate securely to the cylinder.

The removable surface-plate m^2 serves as a base, on which the form of type is fastened, said plate being removed for the more convenient fastening of the type-form thereon, and being then introduced through the

aperture k , or through the similar aperture in the frame a , at the opposite end of the cylinder.

To prepare the press for operation, after the types have been arranged upon the printing-cylinders, the roller t is turned up out of the way, and the roller o , supplied with a strip of paper of the desired length, is put in place, and the roller t brought into the position shown in fig. 1.

The press is then put in motion, and the endless belts v unwind the paper from the paper-roller o , on to the endless frisket h , and the projecting points n , on the cross-pieces m of the frisket, pierce and thus hold the paper, which is drawn forward between the printing-cylinders b and c , receiving an alternate impression on each side. Thence being drawn on, it passes between the cylinders c and d again, receiving an alternate impression on each side of the paper, the sheet being thus perfected.

The paper is thence drawn toward and delivered on to the discharging-apparatus, the projecting pins s upon which pierce the paper, and hold it until it is cut off and discharged by the action of the flies.

As the cylinder p' rotates, the cross-bars w' are carried forward, the ends thereof sliding in contact with the inner side of the guides, or cams x' , which are curved in such a manner as to cause said cross-bars w' to approach and wind around the cylinder p' , and occupy their proper recesses therein, until said bars, by the revolution of cylinder p' , are brought to those points marked o^2 of said two cams x' , where, being suddenly released by the breaks in said cams, the cross-bars w' fly, with considerable force, cutting off the sheets of paper, and coming down upon springs p^2 , on the cams x' , and the following-fly, made up of the springs f^2 and cross-bars g^2 , having more elasticity and being unopposed, except by the floor or table, or pile of papers thereon, force each sheet, as it is cut off, directly down upon the table, floor, or other receptacle below, or pile of papers thereon.

At the same time that the knives y' come into operation, the auxiliary fly, made up of plate z' and other described parts, is thrown out by the action of the cams d^2 , and relieves the cut-off sheet from the hold of points s .

Two printing-cylinders, the surface of each of which consists of half type and half blanket-spaces, such as described, may be employed, if desired, by substituting, for the cylinder b , a plain blanket-cylinder, and by placing below the cylinder d another plain blanket-cylinder; also, by employing two endless friskets, instead of the one, each of the two being similar to the one described, except that each is only half as long as the one described; also, by locating the drum g on a horizontal line with the cylinder d ; also, by correspondingly increasing the height of frame a .

The speed of the unwinding and dampening-belts v , or blanket, must correspond with that of the periphery of the printing-cylinders.

In place of the endless belts v to unwind the paper, a single endless belt, or blanket, corresponding in width with the width of the paper, may be employed, to answer the double purpose of dampening and unwinding the paper.

The endless frisket h , and also the side belts attached to said frisket to move it, may be made of metal, leather, canvas, or any other flexible material; or in place of employing the flexible steel belts described for driving the frisket, a metallic wire rope, or a belt composed of separate metallic plates jointed together, or an endless chain, may be employed, the drums around which the frisket and attached driving-belts turn, when chains or belts of jointed metallic plates are employed, being made in the shape of a triangular, square, pentagonal, or other polygonal prism, or so as to present many flat faces of equal area for

the links, or plates of the chain to act upon without slipping; or the frisket and side belts might be made of one piece.

An aperture, similar to the aperture k^2 , fig. 2, may be formed in each side of the frame a , opposite each of the printing-cylinders, to facilitate the placing of the type-forms thereon, if desired.

The gearing by which the printing-cylinders are operated may all be arranged on one side of the frame, if desired, and thus leave the apertures through which the forms of type are placed upon the printing-cylinders unobstructed.

It is not necessary that the type and blanket-spaces of each of the printing-cylinders should each be in a single division or section, but the type-space of each cylinder may, if desired, be subdivided into two or more equal spaces, and the blanket-space similarly subdivided, the subdivisions being arranged so as to alternate on the surface of each cylinder.

Various forms may be given to the mechanism which constitutes the base of the flies, or to which the flies are attached, still preserving what is the essential feature of this part of my invention, to wit, the combination of the flies with a rotary, instead of a stationary base. Thus, instead of attaching the flies to a cylinder, such as p^1 , as a base, they may be attached to an endless belt, or to a rotating prism, either of triangular, square, pentagonal, or other polygonal shape, the necessary changes being made in the form of the tracks, or cams x .

Having thus described my invention,

I claim, and desire to secure by Letters Patent—

1. The combination of a series of two or more printing-cylinders, the surface of each of which is equally

divided into equal alternate sections or divisions of type-space or spaces and blanket-space or spaces, or the combination of two or more such cylinders with two or more plain blanket-cylinders, for the purpose of printing both sides of a sheet of paper at one operation, substantially as set forth.

2. The device, consisting of the endless flexible or jointed frisket l , with its projecting sharp points n , or any mechanism for holding the paper thereon, in combination with the endless flexible side belts k l , attached to said frisket for propelling it, substantially as set forth.

3. A removable sliding surface-plate, m , in combination with any printing-cylinder, to facilitate the placing of the type-forms on such cylinder.

4. The rollers p q s t u , endless belts or belt or blanket v , roller r , with its springs or weights, in combination with the paper-roller o , in the manner and for the purpose substantially as shown and described.

5. Giving the fly or flies of a printing-press a revolving motion, by attaching it or them at one of its or their ends to a rotary or movable base, to effect rapidity of discharge, substantially as set forth.

6. The fly v w , with its serrated knife y , the auxiliary fly z c , and the following-fly f^4 g^4 , in combination with the cylinder p , projecting points s , cams x k^2 , and cams d^2 , by means whereof the continuous strip of printed paper is cut into sheets of the desired size, and discharged, substantially as set forth.

JOHN K. WRIGHT.
